JAMES ROBERT STEELE, OF OWEGO, NEW YORK, ASSIGNOR TO STEELE RAIL ANCHOR COMPANY, INC., OF OWEGO, NEW YORK, A CORPORATION OF NEW YORK.

RAIL-FASTENING.

1,269,561.

Specification of Letters Patent. Patented June 11, 1918.

Application filed April 27, 1917. Serial No. 164,873.

To all whom it may concern:

Be it known that I, JAMES ROBERT STEELE, a citizen of the United States, and a resident of Owego, in the county of Tioga and State 5 of New York, have invented a new and useful Rail-Fastening, of which the following is a specification.

The invention is more particularly an improvement upon the fastening disclosed in 10 my Patent, #1,224,426, of May 1, 1917, which covers a combination of fasteners having plain, *i. e.* unthreaded, shanks inserted diagonally in the tie and integral, laterally bent heads engaging over the rail 15 base, and a load-receiving plate between the rail and tie, called for convenience the tie-plate, having inclined openings which are fitted closely by the plain diagonal shanks, so that the plate and fasteners constitute a 20 substantially rigid unit, wherein the load on the plate is largely transmitted to the fasteners, and the tie, tie-plate, and fasteners are all firmly bound together, the plate holding the fasteners down and keeping them 25 from spreading, and the fasteners in turn holding the plate against pounding movement on the tie and relieving its pressure thereon. In accordance with the present invention, the fasteners, while rigid as to their 30 coöperation with the tie-plates, are resiliently yielding in their portions above the tie-plate and having their heads so constructed as to bear upon the top of the rail base at points laterally remote from the holes in 35 the plate, thus providing an elastic leverage which accommodates undulation of the rail without permitting longitudinal creeping thereof, causes upward pressure on the heads to bind the shanks in the plate holes, thus 40 keeping them from working up, guards against breakage of either rail or fastening, and does not enlarge the openings in the tie.

In the preferred form of the fastener or spike, also constituting a feature of the invention, the head is formed by bending over the upper portion of the shank, entirely at one side of the shank and without upsetting, to form an arched or recurved head, which insures a point of bearing upon the rail base 45 laterally remote from the hole in the plate and the edge of the rail base, and precludes injury to the fasteners, when being driven, by continued hammering after the fasteners are home.

50 The tie-plate may be one of ordinary size

and weight, or one substantially thinner or narrower, or both. Its function in the fastening is not so much to distribute load over the surface of the tie, as to apply it to the shanks of the fasteners without permitting 50 the rail to ride thereon, and to tie them together horizontally so that they may not spread; and one part of the invention comprehends a plate of narrow or strap-like dimensions, having insufficient area to keep it 55 from sinking into the wood of the tie were it not for support received from the fasteners, but constituting an effective tension and load-transmitting member for the purposes described.

70 In the accompanying drawings:

Figure 1 is a vertical section through a rail, tie and tie plate, transverse to the rail, showing one of the fasteners in elevation in the plane of section;

75 Fig. 2 is a plan view thereof; and

Figs. 3 and 4 are views, similar to the foregoing, of a somewhat different construction.

5 is a rail and 6 a wood tie. 2 or 2^a designates the tie plate, which is interposed between the rail and tie, and which as stated in my said application may be of thinner material than ordinarily employed, because of the support received from the fasteners 85 inwardly of its ends. For the same reason, and because the plate is not so much to distribute the load over the tie as to apply it to the fasteners, and to serve as a connection therebetween, the tie plate may be made very 90 narrow like a strap, as shown in Fig. 2, instead of being of a conventional width such as illustrated in Fig. 4. Holes 30 are formed in this tie plate at opposite sides of the rail, at such angles that the downward 95 prolongations of their axes extend transversely inward beneath the rail at substantial inclinations, preferably in the neighborhood of 50° to the horizontal. The said holes are spaced a suitable distance apart 100 lengthwise of the rail, and their axes may lie in parallel vertical planes which are normal to the axis of the rail, though they may be formed and the fasteners set at a double diagonal as in my prior construction, if desired.

105 The fasteners 9 and 10, or 9^a and 10^a, of which two are usually sufficient, one at each side of the rail, and in this instance preferably of identical form, have plain, *i. e.* un-

threaded, shanks, and integral lateral heads. The said fasteners are desirably manufactured from lengths of cylindrical stock having a portion at the end bent sidewise to 5 form the head, the round form of the shank being of advantage for the reasons, among others, set forth in my earlier application. The material used is to be of elastic or semi-elastic nature, a soft, rivet steel being suitable for the purpose and of reasonable cost, though springier and more expensive steels may be used if desired.

The shanks, or at least their upper portions, and the circular holes in the tie plate 15 are sized for a close fit, best results being obtained when the shank is as nearly as may be the same diameter as the hole, for example, a seven-eighths inch shank in a seven-eighths inch hole, as such dimensions are 20 usually measured. The shanks are introduced through these holes into the tie, in diagonal directions coinciding with the axes of the openings, the amount of the inclination being such as to cause a substantial part 25 of the load borne by the rail, and by it applied to the tie plate, to be imposed upon the fasteners. As indicated above an angle of about 50° has been found particularly suitable. It will be observed that the fasteners receive the load wholly through the 30 plate, the latter guarding the shanks from detrimental direct action thereon of the rail. In my prior application I have illustrated blunt pointed fasteners inserted into bored 35 holes in the tie, and provided with means for interlocking therein. As here shown, I may, and preferably do, provide the shanks with sharp points, and drive them either without pre-forming the holes at all or with only 40 partial pre-forming. Furthermore, and especially with the improvement now presented, it is unnecessary to engage the fasteners with each other in the tie, or to provide any special means for anchoring them, the fasteners being held in place under load by 45 downward pressure of the tie plate on the shanks, and under upward movement of the rail by friction and reaction in the tie plate added to the resistance to withdrawal in 50 the tie.

From the foregoing it will be perceived that the fasteners are so held at the neck that the heads cannot move away from the rail flange, either upward or laterally, and 55 that load on the plate cannot force it downward into the tie away from the heads, to the injury of the wood. Any slight downward movement which occurs is a movement of the plate and fasteners together, the 60 heads remaining in engagement with the rail flange. The load on the rail becomes one of the factors holding the fasteners down, and the latter in turn support the plate and relieve the top of the tie of pressure. Furthermore, the fasteners do not permit the 65

plate to jump up and down under the rail, and consequently the destructive effect upon the wood resulting from such action is avoided. The plate acts to receive the load from the rail and to transmit it in large 70 measure to the shanks, which distribute it in the interior of the tie. In so doing the plate guards the shanks against direct engagement by the rail base and thereby avoids the detrimental effect which would be produced if the rail, which as hereafter described has a certain freedom of movement, were allowed to ride upon the shanks. In the direction of its length the plate acts as a 75 tension member, tying the fasteners together 80 and thereby enabling them to sustain the load which they receive.

The heads, of which two forms are illustrated, designated respectively 12 and 13, and 12^a and 13^a, are made to grip the rail 85 flange at points of bearing located inward from vertical lines which would be projections of the points where the shanks engage in the tie plate, so that a leverage is obtained which brings into play the elasticity of the 90 fasteners above the plate, while tending to bind them thereto by lateral pressure in the tie plate openings, when the rail presses upward in undulation. I find that with relatively long heads having a lateral projection 95 of an inch more or less, and other factors substantially as indicated, upward force exerted beneath the extremities of the heads is rendered incapable of withdrawing the fasteners, which may nevertheless yield without 100 receiving a permanent set and without loosening, and thus coöperate with the rail in movement. Naturally the length of the head, measured laterally from the shank, may be varied according to the stiffness and 105 thickness of the material used.

The heads 12^a and 13^a of Figs. 3 and 4 are straight as in my prior application, but are formed at such angles to the shanks as to cause them to strike first upon the rail flange 110 at their ends. As the driving is completed the heads become slightly sprung and may even appear to lie flat upon the rail flange; but as a matter of fact the points of gripping and consequently of upward thrust 115 will always be toward the ends. In this connection it will be understood that it is desirable to make the angle of the heads to the shanks such that in event of the fasteners being driven as far as possible the heads will 120 not become sprung beyond the elastic limit.

Instead of straight or substantially straight heads, I prefer to employ arched or gooseneck heads such as illustrated in Figs. 1 and 2. These heads are so designed as to 125 cause their curvature to commence very close above the tie plate, when the parts are in final position, the heads thence arching upward and inward over the edge of the rail flange and downward into contact with the 130

inclined surface thereof at their extremities, at points inward of the edges. This form of head is cheaper and easier to manufacture than a straight head, requiring less material 5 and a simple bending operation, as against bending and upsetting for a straight head, and possesses numerous special advantages in operation. The fibers of the metal being substantially undisturbed a longer-wearing 10 fastener is produced, and the elastic action is better, the latter being due also to the fact that the bending will occur in the neck above the tie plate rather than in the head, as in the straight construction. Furthermore, 15 the arched head is very difficult to damage by overdriving. Again, the blows which must necessarily be delivered upon the region of greatest prominence, that is the top of the arch, which is between the shank 20 and the bearing extremity, cannot affect the elasticity of the lower portion which yields in undulation; and always, of course, a point of bearing remote from the shank is insured. By comparison of Figs. 1 and 3 it will also 25 be observed that substantially all of the lateral extent or projection of the arched head is rendered effective in leverage to bind the shanks in the tie plate, because the shanks as they emerge upward from the plate do 30 not have to be carried outward to any extent before passing inward over the rail flange.

From the foregoing it will be understood 35 that the fasteners can give to the vertical movement of the rail, without at any time relaxing their grip, and that all of the yield is above the tie, owing to the upper or neck portions of the shanks being rigidly stayed and held in the tie plate, so that the parts 40 in the tie are in effect insulated from the resilient play which goes on above. The results secured in this way are quite different from those that would be obtained if the fasteners were placed in wooden ties without 45 means for holding them at the necks, as in the latter case the bending of the fasteners under the leverage of the heads would occur in the tie, enlarging the tie holes, with consequent loss of resistance to withdrawal 50 and opening of the way for entrance of water.

What I claim as new is:

1. A rail fastening comprising a tie plate with diagonal holes at opposite sides of the rail, and fasteners having plain shanks which fit closely in said holes and thence extend diagonally in the tie beneath the rail so that the tie plate rests on and holds the fasteners, and integral laterally projecting heads, the relation of which to the diagonal of the holes and shanks is such as to cause them to bear upon the rail flanges primarily toward their ends, the fasteners being elastic above the tie plate.
2. A rail fastening comprising a tie plate

with diagonal holes at opposite sides of the rail, and fasteners having plain shanks which fit closely in said holes and thence extend diagonally in the tie beneath the rail so that the tie plate rests on and holds the 70 fasteners, and integral laterally projecting heads, the relation of which to the diagonal of the holes and shanks is such as to cause them to bear upon the rail flanges primarily toward their ends, the fasteners being elastic above the tie plate and their heads being of such length that upward pressure beneath their ends cannot effect withdrawal.

3. A rail fastening comprising a tie plate with diagonal holes at opposite sides of the 80 rail, and fasteners having plain shanks fitting closely in said holes and thence extending diagonally in the tie beneath the rail at angles of about 50° to the horizontal, and being unconnected within the tie, and integral lever heads the relation of which to the diagonal of the shanks and holes is such as to cause the heads to bear upon the rail flanges primarily toward their ends, the fasteners being elastic above the tie plate.

4. In a rail fastening, and in combination with a rail and tie, fasteners of elastic material at opposite sides of the rail having integral lever heads gripping the rail flanges toward their ends, and plain shanks disposed 95 diagonally in the tie, and a tie plate having diagonal holes closely engaging the necks of the fasteners so as to rest thereon and hold the same, the portions of the fasteners above the tie plate being under tension.

5. A rail fastener comprising a tie plate having diagonal holes at opposite sides of the rail, and fasteners comprising plain cylindrical rods of elastic material pointed for driving, and having their upper portions 105 bent to form heads in such relation to the shanks as to cause the heads to bear point first upon the rail flanges when the shanks are driven in the direction of the diagonal holes, the tie plate resting upon and holding 110 the necks of the fasteners.

6. A rail fastening comprising fasteners of elastic material, their shanks extending diagonally inward from opposite sides beneath the rail, and a tie plate having close-fitting openings whereby it holds and rests upon the upper portions of the diagonal shanks, the fastenings having integral arched lever heads adapted to bear at their ends upon the rail flange.

7. A rail fastening comprising the combination of a tie plate having diagonal openings, their axes directed inward beneath the rail-seat portion of the plate, and fasteners having shanks formed to fit closely in said 125 openings and integral gooseneck heads to grip the rail flange at their extremities.

8. A rail fastening comprising a substantially rigid tie plate having fastener-receiving holes at opposite sides of the rail base

seat and fasteners having shanks filling said holes to grip therein by lateral pressure and lock the plate and shank rigidly together, said fasteners having their shanks extended 5 below the plate to anchor the plate and rail to the tie and having above the plate laterally extending heads yieldingly engaging the rail base at points laterally remote from the openings in the plate, whereby vertical pressure 10 of the rail on the fastener heads locks the fasteners and plate rigidly together and relative vertical movement of the rail and plate is permitted by the yielding of the heads of the fasteners.

15 9. A rail fastening comprising a substantially rigid tie plate having inwardly inclined fastener-receiving holes at opposite sides of the rail base seat and fasteners having plain shanks to fit closely in said holes 20 to lock the plate and fasteners rigidly together, and project diagonally into the tie below the plate and above said plate having yielding laterally extending heads with their rail base engaging portions remote from the 25 shank, whereby vertical pressure of the rail base produces lateral as contradistinguished from longitudinal strain on the shank within the openings in the plate and relative vertical movement of the rail and plate is permitted by the yielding of the head of the 30 fastener.

10. A rail fastening comprising fasteners having plain shanks and integral lateral heads and formed to extend diagonally in 35 the tie with their heads in engagement with the top of the rail flange, and a narrow member to be interposed between the rail and tie having inwardly inclined holes toward its ends formed for close engagement 40 with the shanks, so as to hold the fasteners and to be held thereby and to transmit the load in substantial measure thereto.

11. In a rail fastening, the combination

of a pair of fasteners having straight plain shanks inserted in the tie from opposite 45 sides diagonally inward beneath the rail toward the central vertical plane thereof and integral laterally disposed heads engaging over the rail flange, and a strap-like member intervening between the rail and tie and connecting the fasteners, said member being of insufficient area to keep it from sinking into the tie if supported solely thereby, and having openings in its end portions whereby it is supported in substantial measure 50 upon the upper portions of the straight diagonal shanks, which it holds and guards from direct action by the rail.

12. A rail fastener comprising a plain shank and an integral arched head, one limb 60 of the arch springing directly from the shank and the other limb terminating in a bearing extremity adapted to engage upon the flange of the rail at a distance from the shank, the top of the arch or driving prominence being between the shank and the bearing extremity.

13. A rail fastener having a plain straight shank and its upper portion curved over entirely at one side of the shank in a natural 70 bend to form an arched head.

14. A rail fastener comprising a plain shank adapted to be inserted diagonally in a tie and an arched lever head merging by a curve into the shank and terminating in a bearing point to engage upon the rail flange.

15. A rail fastener having a plain shank the upper portion of which is bent over at one side in the form of a recurved hook to constitute an arched head the extremity of which is designed to bear upon the top of the rail base at a point remote from the shank.

JAMES ROBERT STEELE.
